UNITED STATES PATENT OFFICE.

OTTO SOINÉ, OF BRUNSWICK, GERMANY.

BALL-MILL.

SPECIFICATION forming part of Letters Patent No. 783,905, dated February 28, 1905.

Application filed March 1, 1904. Serial No. 196,113.

To all whom it may concern:

Be it known that I, OTTO SOINÉ, engineer, a subject of the Emperor of Germany, residing at Brunswick, Duchy of Brunswick, Empire of Germany, have invented certain new and useful Improvements in Ball-Mills, of which the following is a specification.

This invention relates to ball-mills wherein a series of balls are disposed in circular alignment and pressed against a more or less perpendicular grinding-surface as centrifugal power is developed by rotation of the supporting means for the balls.

Heretofore ball-mills have been constructed with complex cases or compartments to receive the balls, and such cases or compartments have been generally closed on three sides and entail considerable expense in the manufacture of this class of mills by reason of the difficulties encountered in accurately and practically casting the cases in the supporting means of which they form a part. The production of these cases or compartments has also materially added weight to the mills, and if repair became necessary it could not be very readily accomplished, and renewal was almost impossible.

The object of the present invention is to include in a ball-mill a rotating body which serves the same purpose as the hollow cases heretofore ordinarily used, but having an arrangement and construction of a very simple and practical nature and wherein the balls are retained in proper position during the operation of the mill and readily removable without requiring a complete or material disassociation of the parts of the mill.

In the drawings, Figure 1 is a vertical section showing a ball-mill embodying the features of the invention. Fig. 2 is a top plan of the same.

Similar letters of reference are employed to indicate corresponding parts in the views.

The rotating body *f* of the mill flares outwardly and downwardly from a conical hub *e* and terminates at its lowest level in a substantially horizontal rim *b*. This body is hollow and rotatably supported, as in the usual construction of all mills of this class, and the periphery of the rim *b* closely engages the

inner portion of the lower terminal of a fixed track-rim *k*, having an inner concave surface against which the balls operate. The rim *b* and the downwardly and outwardly flared body *f* are radially divided by vertical partitions *h*, which terminate at a distance inwardly from the concave face of the fixed rim *k* and have their upper edges below the corresponding edge of said rim. A driver *i* is secured to one side of each partition and formed of material harder than the partition, the several drivers being of less radial extent than the partitions, and their contacting faces are inclined to effectively drive the balls which are engaged thereby. The drivers increase in thickness toward their outer ends to prolong their wearing characteristics.

Balls *g* are disposed in the compartments formed between the successive drivers and partitions, the balls being of such diameter as to have loose play in the several compartments. By reason of the flaring construction of the body *f* and the upper open nature of the fixed rim *k* the balls can be readily withdrawn from the compartments and replaced in the latter. It is necessary to provide some means for retaining the balls in their compartments during the operation of the mill, and in conformity with the present invention this means must be readily removable. To attain this result, a hollow frustoconical sleeve or cover *c* is provided and formed with a hub *d*, corresponding in contour to and removably and snugly fitted over the hub *e* of the body *f*. The hollow sleeve or cover *c* has a downwardly and outwardly curved flare and terminates in a lower enlargement *a*, which has an upwardly-inclined contacting edge normally located adjacent to the balls. When the cover *c* is in applied position, the distance between the lower enlarged edge and the upper edge of the fixed rim *k* is materially less than the diameter of the balls, and hence the latter are free to move, but cannot fly out of position from between the partitions and drivers. The balls are always thrown outwardly, and their inward movement to too great an extent is resisted by the lower enlarged edge of the cover. The cover also rotates equally with the body *f*.

f and the balls carried by the latter and is held in rotatable relation with respect to the hub *e* by a feather-and-groove construction set up between the two hubs *d* and *e*. An ordinary key might be used for the same purpose, but as particular means for establishing a jointure between the two hubs *d* and *e* is not essential and may be varied at will no particular means for this purpose have been shown.

From the foregoing description the operation of the mill will be readily understood, and, further, such modifications as legitimately lie within the scope of the invention will be adopted at will.

Having thus described the invention, what is claimed as new is—

1. A ball-mill having a rotatable body which downwardly and outwardly flares to a substantially horizontal rim, the latter being provided with radial partitions, a fixed rim with

which the rim of the body coöperates, and a cover removably and fixedly held on the upper portion of the body and having its lower edge located inwardly at a distance from the upper edge of the fixed rim. 25

2. A ball-mill having a rotatable body with partitions radially arranged thereon, a driver secured to one side of each partition, a fixed rim adjacent to which the said partitions have 30 rotation, balls interposed between the drivers and partitions, and a cover freely removable from and fixedly held by the body, the said cover having its lower edge extending over a portion of the partitions. 35

In testimony whereof I have hereunto set my hand in presence of two subscribing witnesses.

OTTO SOINÉ.
